UNITED STATES PATENT OFFICE.

ORIN F. PERRY AND ORIN F. PERRY, JR., OF NEW YORK, N. Y.

Mounting for Rapid-Fire Guns and the Like.

1,273,178.

Specification of Letters Patent.

Patented July 23, 1918.

Application filed August 9, 1916. Serial No. 113,953.

To all whom it may concern:

Be it known that we, ORIN F. PERRY and ORIN F. PERRY, Jr., citizens of the United States, residing at 96 Riverside Drive, New York city, N. Y., have invented certain new and useful Improvements in Mountings for Rapid-Fire Guns and the like, of which the following is a clear, full, and exact description.

10 This invention relates to an improvement in adjustable mountings for supporting rapid fire guns, field telescopes, and other similar instruments, upon the ordinary motor-cycle or bicycle. The object of the invention is to improve such mountings for making the same both secure and quickly detachable and easily adjustable by the rider at all times.

In our preferred embodiment, we have 20 shown the mounting as adapted for supporting a rapid fire gun upon a motor-cycle.

A further object is to provide a mounting for the gun which will be light and compact, not interfering with the operation of 25 the motor-cycle by the rider thereof, and which will furnish a solid, rigid base for holding the gun in position for firing.

The present improvement is designed to 30 enable one man to both operate the motor-cycle and also to use the gun when required, thus avoiding the necessity of carrying the gun with one or two extra passengers in a side car which has heretofore been the practice. It is contemplated that the best results 35 in the use of this gun will be obtained when the motor-cycle is stationary rather than in motion, and while stationary the machine will be supported in upright position either by the legs of the rider or by the usual 40 fixed stand common to such motor-cycles. The mounting of the gun is so arranged that it may be easily operated and adjusted without the rider leaving his seat.

Further objects and advantages of the improvement will become apparent from the 45 following specification and accompanying drawings, which show the preferred embodiment of our invention and in which—

Figure 1 is an elevation of the motor-cycle and gun mounted thereon;

Fig. 2 is a detail section through a foot rest of the motor-cycle along line 2—2 of Fig. 1;

Fig. 3 is a section taken through the gun supporting frame along line 3—3 of Fig. 1 looking downwardly;

Fig. 4 is a side elevation of a portion of the frame shown in Fig. 3;

Fig. 5 is a section taken along line 5—5 of Fig. 3;

Fig. 6 is a section taken along line 6—6 of Fig. 5 showing the worm drive for the vertically adjusted stem;

Fig. 7 is an enlarged detail of a lever-operated clamping device for holding the gun bracket in different angular elevations;

Fig. 8 is a section taken along line 8—8 of Fig. 6 showing another side of the worm drive;

Fig. 9 is a modification of a clamping device for securing both horizontal and angular adjustments of said gun bracket; and

Fig. 10 is a detail of the gun holding clamp.

Referring more particularly to the drawings, 1 indicates the frame of a two-wheel motor-cycle, having a front wheel 2 and a rear wheel 3 and motor 4 mounted within the frame. The frame 1 has the usual steering head 5 at the front part thereof, and seat support 6 for the saddle 7 upon which the rider sits at the rear part thereof. The usual steering handle bars are indicated at 8, and a swinging stand 9 is mounted at the rear of the frame for supporting the machine when at rest in the usual way. Foot rests for the rider are fixed to the frame at the lower part thereof, one at each side, one of said foot rests being shown at 10. The other details of the motor-cycle are of the usual construction and need not be more specifically described.

The supporting frame or mounting is attached to the motor-cycle for supporting a rapid fire gun such as 11, so that said gun may be easily adjusted for aiming and rapidly manipulated for firing by the rider of the machine when in position upon the saddle 7. The gun should be so mounted that the handle stock 12 and trigger 13 are within convenient reach of the hands of the rider, and for more convenient manipulation a spade grip such as 14 may be provided rather than the usual shoulder stock.

The construction of the mounting for supporting the gun is as follows: An upper

horizontal member 15 has four downwardly extending vertical struts, two at each side of the machine such as 16 and 17 shown in Fig. 1, which struts are connected at their upper ends to the member 15 and their lower ends to the foot rests such as 10. The forward strut 16 for instance, is connected at its upper end at 20 to the member 15 and at its lower end at 18 to the foot rest 10. The rear strut such as 17 is connected at its upper end at 21 to the member 15, and at its lower end to the rear end of foot rest 10 at 19. The detail of the connection 19 is shown in Fig. 2. The four vertical legs or struts 15 are reinforced below said upper member 15 by a lower member or brace 25 which also non-rotatably supports a tubular socket 26 for the gun supporting stem, as will be hereinafter described. In addition to the four vertical struts, there is provided a recoil strut 22 connected at its forward end at 23 to the brace frame 25 and extending in a slightly inclined direction downwardly toward the rear where it is fastened to the bicycle frame at 24. The recoil strut 22 serves to brace the gun 11 against any backward movement during both the firing and during the travel of the machine,—in other words, receives at all times any rearward thrust imparted by said fire-arm and its frame.

Referring more particularly to Figs. 3 and 9 inclusive, we will now describe the means for adjusting and aiming the gun. The member 15 has centrally therein a vertically disposed tubular socket 26, which receives a vertical stem 27 which is swivelly mounted in said socket and therefore adapted to turn on its vertical axis. Pivoted at 28 upon the upper part of the stem 27 is the gun bracket 29 which swings on the pivot 28 on a horizontal axis to allow the gun to be adjusted at different angular elevations. The gun is detachably secured to the bracket 29 by lateral pins 100 on said gun, which engage slots 101 in said bracket and by a clamping device 102 shown in detail in Fig. 10. The swiveled stem 27 is further provided with circular rack teeth 30 engaged by an operating pinion 31, which pinion is mounted in suitable bearings 32 in a casing on member 15. It will therefore be understood that the rack teeth of stem 27 are operable by the pinion 31 at all portions of its periphery so that said stem may be elevated and lowered in any position into which it may happen to be turned. Pinion 31 is integrally mounted with small worm wheel 34 (see Figs. 6 and 8), which worm wheel is operated in turn by the worm 35 on shaft 36 rotated by the hand crank 37. This form of worm drive tends to maintain the vertical stem 27 in any of its vertical adjustments. In order to secure stem 27 in different swiveled positions, a clamping

collar 38 is provided by splitting the upper portion of the tubular socket (see Figs. 3 and 4) which collar encircles said stem 27 and is locked about the stem 27 by a cam lever 39. When this lever 39 is thrown down from the position shown in Fig. 4, the stem 27 is free to be turned on its vertical axis to swing the gun 11 into any horizontal position. When the lever 39 is thrown to the position shown in Fig. 4, the collar 38 securely clamps the stem 27 and holds it fast in its adjusted position. In a similar manner the gun bracket 29 is clamped in various adjusted positions on its pivot 28. As shown in Fig. 7, the bracket 29 is received between separated bearing faces 40 and 41 of the stem 27. The pivot shaft 28 has a head 42 at one side thereof and head 43 at the other side thereof, and a cam lever 44 coöperating with cam 45 on the bearing face 40 is adapted to lock said bearing faces 41 and 40 securely against the bracket 29. For instance, when lever 44 is in the position shown in Fig. 7, bracket 29 would be loose enough to adjust, but when the lever 44 is operated to swing the high side of its cam against the high side of the coöperating cam 45, the two bearing faces 40 and 41 will be securely clamped against bracket 29.

In the modification shown in Fig. 9 the vertical stem 27' having a squared cross section, is employed in place of the cylindrical stem 27 so as not to turn in its socket. It is understood that this vertical stem 27 has the usual rack teeth at one side thereof for engaging a pinion similar to 31. The upper end of stem 27' is spherically shaped as at 50, upon which spherical end is supported a split cup 51 having lugs 52 and 53, through which passes clamping bolt 55. A cam lever 56 pivoted from one end of said bolt 55, coöperates with a cam 57 on lug 53 to close said lugs 52 and 53 together and thus clamp the cup 57 upon the spherical head 50. The cup 57 has fixed thereto the gun supporting bracket 29' similar to 29. It is understood that when lever 56 is in one position, the cup 57 is loose upon the spherical head 50 and that the bracket 29' may therefore be adjusted to any angular position whatsoever, both horizontally and vertically. When the adjustment is obtained the lever 56 may be thrown to securely clamp cup 57 upon the spherical head 50 and thus hold the gun bracket in its adjusted position. It will be noted that in this modification a single hand-operated clamping lever such as 56 may be manipulated to give as much adjustment for the gun mounting as the operation of two separate clamping levers 39 and 44 of the first modification.

In the operation of this improved fire-arm mounting, the motor-cycle is first brought to rest as above stated, the rider remaining astraddle of the machine and either support-

ing it in upright position with his legs or throwing down the rest frame 9 at the rear to provide a further support. In this position the rider has the gun directly in front of him and if necessary elevates it to the proper position by turning crank 37. Then if necessary to swing the gun horizontally, clamp lever 39 is loosened and the gun is swung around. If a further angular adjustment is required, clamp lever 44 is operated to loosen its clamp, whereupon the gun may be swung up and down to different angular positions. It may be desirable to operate the gun with these clamps all in loosened position so that the gun can be rapidly turned from side to side and up and down, but if desirable any one of the adjustments may be clamped in position for more steady firing in one direction.

20 It will be observed that with this improvement we have provided a very mobile firing unit which may be rapidly shifted from place to place and which may be easily aimed and fired at all times either while 25 the motor-cycle is stationary or in motion, with the least amount of attendance and trouble.

It is obvious that the improvement is susceptible of wide variations in detail, and we 30 wish it to be understood that the scope of our invention is not to be limited to the particular embodiment shown, which is merely preferred for illustrative purposes.

What we claim as new is:—

- 35 1. The combination with a two wheel cycle having a foot-rest at each side thereof, of a mounting, carried by said foot-rests, for supporting a rapid fire gun or the like.
2. The combination with a two-wheel 40 cycle, having a foot-rest fixed at each side thereof, of a mounting for supporting a rapid fire gun or the like, comprising vertical struts mounted on the foot-rests of said cycle.
- 45 3. The combination with a two-wheel cycle, having a foot-rest fixed at each side thereof, of a mounting for supporting a rapid fire gun or the like, comprising a pair of front and rear vertical struts at each side 50 of said cycle frame, said front struts connected to the forward portions of said foot-rests and said rear struts connected to the rear portions of said foot-rests.
4. The combination with a two-wheel 55 cycle, comprising a frame having a steering head at the front part thereof, and a seat support at the rear part thereof, and foot-rests at each side of the lower portion thereof, of a mounting for supporting a rapid 60 fire gun or the like, located adjacent the head thereof, comprising vertical struts connected with the foot-rests of said cycle, and a rearwardly inclined recoil brace connected 65 with said cycle frame adjacent the seat support.

5. The combination with a two-wheel cycle, comprising a frame having a steering head at the front part thereof, and a seat support at the rear part thereof, and foot-rests at each side of the lower portion thereof, of a mounting for supporting a rapid fire gun or the like, located adjacent the head of said frame, comprising vertical struts connected with the foot-rests of said cycle, and a rearwardly inclined recoil brace 70 connected with said cycle frame adjacent the seat support, a vertical stem swivelly carried in said mounting, a bracket attached to said gun and pivotally mounted on said stem for swinging on a horizontal axis, said 75 vertical stem having circular rack teeth thereon, an operating pinion for engaging said rack teeth, and a worm drive comprising a hand crank for operating said pinion.

6. The combination with a two-wheel 85 cycle, comprising a frame having a steering head at the front part thereof, and a seat support at the rear part thereof, and foot-rests at each side of the lower portion thereof, of a mounting for supporting a rapid 90 fire gun or the like located adjacent the head thereof, comprising vertical struts connected with the foot-rests of said cycle, and a rearwardly inclined recoil brace connected 95 with said cycle frame adjacent the seat support, a vertical stem swivelly carried in said mounting, a lever operated clamping device for holding said vertical stem in different adjustments, a bracket attached to said gun and pivotally mounted on said stem for 100 swinging on a horizontal axis, a lever operated clamping device for holding said bracket in different angular positions, said vertical stem having circular rack teeth thereon, an operating pinion mounted for 105 engaging said rack teeth, and a worm drive comprising a hand crank for operating said pinion.

7. The combination with a two-wheel 110 cycle, comprising a frame having a steering head at the front part thereof and a seat support at the rear part thereof, and foot-rests at each side of the lower portion thereof, of a mounting for supporting a rapid 115 fire gun or the like and located adjacent the head thereof, comprising upper and lower horizontal members and four vertical struts extending downwardly therefrom and connected with the foot rests of said cycle, a rearwardly inclined recoil brace connected 120 with said cycle frame adjacent the seat support, a tubular bearing socket supported between the upper and lower members of said mounting, a vertical stem swivelly mounted in said socket bearing, a lever operated clamping device for holding said vertical stem in different adjustments, a bracket attached to said gun and pivotally mounted 125 on said stem for swinging on a horizontal axis, a lever operated clamping device for 130

holding said bracket in different angular positions, said vertical stem having circular rack teeth thereon, an operating pinion mounted for engaging said rack teeth, and
5 a worm drive comprising a hand crank for operating said pinion, and a casing inclosing said operating pinion and said worm drive.

Signed at New York city this 28th day of July, 1916.
